ABRASIVE TOOL

Orello S. Buckner, Westboro, Mass.

Original application May 31, 1927, Serial No. 195,383. Divided and this application July 16, 1931, Serial No. 551,133

19 Claims. (Cl. 51—209)

This application is a division of my application filed May 31, 1927, Serial Number 195,383, for Abrasive tools and processes of making the same and relates to the abrasive tools made by the 5 processes disclosed therein.

Abrasive or attrition materials, such as corundum, emery, artificial corundum, crystalline alumina, carbide of silicon and other well known forms of granular abrasives, are usually composed of irregularly shaped grains, except in the 10 case of certain crystalline forms which are of regular formation. That is, so far as I am aware, all forms of abrasive grains are unequidimensional, and while most granular abrasives contain a substantial proportion which are distinctly 15 elongated, the large proportion of elongated grains is usually particularly apparent where the grains are of the larger sizes, such as are generally employed in the construction of abrasive tools which are to be used for rough work, such 20 as cleaning castings, or where a heavy chip is to be removed. Abrasive grains of elongated formation necessarily have correspondingly flattened sides, which are much less effective, when engaged 25 with the work, than the ends thereof, even though the ends may not be sharply pointed or knife edged.

In the construction of abrasive tools such as blocks, wheels, cylinders, etc., it is customary 30 to mix abrasive material with various forms of organic or ceramic bonds which are adapted to be softened or fused when subjected to heat, then to place the mixture in a mold of the shape desired and subject the mass to considerable pressure, so that it is compressed into a cake, which is 35 then baked, causing the bond to become softened or fused, so that, when it hardens, on cooling, the grains will be firmly bound together.

In performing this process, the grains of abrasive have been fixed in the bond in practically the 40 positions in which they chance to fall, when placed in the mold, so that, while some of the elongated grains are likely to lie in approximately perpendicular relation to the work engaging face of the tool, much the greater proportion thereof are 45 likely to lie with their sides either in parallel relation to the face, or at various angles between parallel and perpendicular positions relative thereto. As this condition obtains throughout the 50 mass, it follows that it is indicative of the condition of the work engaging face at any time.

The degree to which an abrasive article is free cutting depends to a large extent on the sharpness of the abrading or cutting surface, and, as it is usually desired that an abrading tool be as

free cutting as possible, any condition which increases the sharpness of the cutting surface without detrimental effect otherwise increases its efficiency. If the elongated grains of abrasive lie mainly flatwise to the surface, it follows that the 60 sharpness of the surface will be decreased by comparison with a condition in which a larger proportion lie in a more nearly perpendicular relation to the cutting surface, assuming that the spaces between the grains are not unnecessarily filled with bonding material. This statement also applies, although possibly in a lesser degree, to abrasive grains which are not distinctly elongated, but have a greater number of pointed portions, or sharp points or edges, as the dullness of the surface will be greater and the cutting effect thereof will be less if their sides lie flatwise to the surface than if the proportion of the pointed portions thereof which are pointed towards the surface is substantially increased.

In other words the sharp or pointed ends of the grains have a much greater cutting effect than the sides thereof, as the sides present practically flat, or nearly flat surfaces to the work, or points having included angles which are relatively large, so that their action is more nearly a rubbing action which dislodges small particles, than a distinctly cutting or severing action. Moreover, an action which is more distinctly a rubbing action has a much greater tendency to 85 cause heat than a cutting action, on account of the fact that the friction is much greater in removing a certain amount of material than it would be if removed by an action which severs.

Where the abrasive grains are largely of elongated formation, and are poured into the mold in the customary manner, the grains lie criss-cross and leave many unfilled spaces, resulting in a tool which lacks solidity and uniformity in its construction. Tests have shown and it is 95 well known to manufacturers of abrasive tools, that the durability of such tools, and the length of service which they will give depends to a substantial extent on their weight per unit of volume, or the density or solidity thereof. In consequence it has been the practice to subject the elongated grains to further treatment to reduce them to a nearly cubical or polyhedral form, so that the solidity of the tool would be increased and each grain would present a correspondingly 100 large number of sharp points, one of which would be likely to form a part of the working face of the tool. This further treatment necessary to produce cubical or polyhedral grains, increases 105

the cost of the abrasive, as compared with the elongated grains before referred to.

The primary object of my invention is to produce an abrading device or tool which will 5 have a substantially increased efficiency, as compared with the efficiency of devices of this character which are made by the methods now generally employed.

Further objects of my invention are to produce 10 an abrasive tool which may be formed largely, or wholly of abrasive grains which are of elongated formation, but which will be practically as solid, or free from voids as when formed from grains of the cubical or polyhedral type, so that 15 the less expensive forms of abrasives may be employed, and, at the same time a tool may be produced which will have increased durability, effective clearance at the cutting points, and an increased number of cutting points in the working face, so that the efficiency thereof will be 20 substantially increased, as compared with tools formed from grains of the cubical or polyhedral type.

I accomplish these objects by producing an 25 abrading device which is principally composed of abrasive grains of elongated, or unequi-dimensional formation, so that one dimension is substantially longer than the others, and by arranging said grains so that they mainly lie side 30 by side and are packed closely together, with their longer dimensions extending in approximately perpendicular relation to the working face, or in radial relation thereto when the tool is of the wheel type and has a circular face, said grains 35 being securely bonded in these positions, so that their ends will be presented to the work and they will have deep settings which will prevent them from being dislodged in use.

Inasmuch as it would not be practicable to arrange 40 the grains in the manner above indicated separately by manual means, I have devised a practical and effective process of making such abrasive articles, whereby a relatively large proportion of the abrasive grains will be bonded in 45 approximately the positions above indicated in relation to the work-engaging face of the particular abrading device which is to be produced. This process, as described in said original application, primarily consists in showering, or otherwise gradually delivering the abrasive material 50 to the mold, receptacle or other receiving means for the abrasive, before final bonding, and while in a freely granular state, and simultaneously subjecting the same to magnetic action, so that 55 the grains will become polarized and turned to point, or to have some tapering portion thereof point in the direction of the lines of force of the electric field, and by arranging the poles in such relation to the abrading surface to be formed 60 that the above described result will be accomplished. Also, as magnetic action is to be employed, and as all, or nearly all abrasives which are likely to be employed are non-magnetic, as a preliminary step in the process, and preferably 65 in connection with the operation of mixing the bond therewith, I provide the grains of abrasive with a coating of magnetic substance which will, in effect, make them sufficiently susceptible to magnetic influence to accomplish the result desired, as by mixing very fine steel dust with the abrasive grains and an adhesive of sufficient strength to hold the steel particles on the surfaces thereof.

For a more complete description of the invention 75 and of the means by which it may be per-

formed, reference is now made to the accompanying drawing, in which:

Fig. 1 is a side view of an annular abrasive tool embodying my invention.

Fig. 2 is a peripheral view thereof.

Fig. 3 is a sectional view of another form of annular tool embodying the invention.

Fig. 4 is a perspective view of a tool of the block type embodying the invention.

Fig. 5 is a greatly enlarged view of one of the abrasive grains employed in the construction.

The process and apparatus, employed in producing the abrasive tools which are the subject of this application, are specifically described in my said prior application, and will be only briefly outlined herein.

As all abrasive grains of the character above referred to are non-magnetic and, as it is an essential, to the process which I employ that they be made susceptible to magnetic influence, a preliminary step in said process consists in coating the grains with a suitable adhesive and then mixing them with iron dust so that the iron dust will become adhesively connected thereto. That is, the grains will be partly, or wholly ferrous 100 coated. These grains are then mixed with a suitable bonding material, and then are gradually showered into a mold of the shape of the tool to be formed, while they are, at the same time, subjected to the influence of a magnetic flux by 105 means of an electro magnet, the poles of which are so arranged that the lines of force thereof extend approximately at right angles to the working face of the tool to be formed, so that, as the grains fall into the mold the ferrous coating on 110 the grains will become polarized. As a result the ends of the grains of elongated formation will have opposite polarities, and there will be a strong tendency to cause the positively magnetized end of each grain to turn towards the 115 negative pole of the magnet, and vice versa, or to turn the elongated grains in the direction of the lines of force of the magnet.

In practice the poles of the electro-magnet are so arranged with relation to a mold of the desired shape that the lines of force therebetween extend approximately in perpendicular relation to the working face of the tool to be produced, so that when elongated grains thus prepared, are showered into the mold, the electrical flux will 125 tend to turn them into positions in which their longer dimensions extend towards the side of the mold which forms the face of the tool. In practice the positioning of the grains take place while they are falling into the mold and after 130 they come to rest therein, the positioning after they are supported in the mold being assisted by an automatic tapping or jarring action on the mold, which tends to dislodge incorrectly positioned grains, so that they may be repositioned by the magnetic attraction.

As the grains are mixed with a suitable bonding material before they are showered into the mold, when the mold has been filled, as above described, it may then be subjected to the usual 140 compressing and baking process, so that the grains, as thus positioned, will be permanently set.

Referring now to the drawing, Figs. 1 and 2 indicate an abrasive tool *a* of the ordinary wheel 145 or annular type, having flat, parallel sides and a cylindrical working face *a'*, and which is composed mainly of elongated grains, as *b*, which are covered partly or wholly with a thin coating *c* of ferrous material, as indicated on a great- 150

ly enlarged scale in Fig. 5. In this instance the grains *b* will be mainly arranged, throughout the entire mass, in approximately radial relation to the peripheral face of the wheel, and flatwise to its sides, as indicated in Fig. 1, so that the working face of the tool will be principally formed by the ends of these grains, as indicated in Fig. 2.

In Fig. 3, an abrasive tool *d* of another annular type is indicated which has a flat working face *e* at each side. In this instance the grains are arranged flatwise to the periphery and perpendicularly to the sides, or faces *e*.

In Fig. 4 a tool *f* of the block type is shown, having a working face *g* at one edge. In this instance the grains are mainly so arranged that their longer dimensions extend in approximately perpendicular relation to the face *g*.

It will be understood that, in practice, all of the grains will not be of elongated formation, but, as practically none of them will be of spherical formation, they will at least be unequidimensional and the tendency of the electric flux will be to cause the more pointed portions to become polarized oppositely to other portions, so that the action of the flux will be to tend to turn the grains so that their pointed ends will point towards one pole or the other of the magnet.

As a result, comparatively few of the grains will be positioned in the tool, so that their sides will be presented to the work, but they will mainly be positioned so that their more pointed portions will be presented thereto, or will form the work engaging face, and this condition will continue as the tool is worn down by use.

It will be understood that the various forms of tools shown are merely illustrative and that the principles involved may be applied to other forms of tools, although so far as I am aware, the most advantageous form is that of the ordinary wheel type shown in Fig. 1, with which the most substantial increase in efficiency has been secured, as compared with similar types of tools in which the grains are arranged as they happen to fall into the mold.

An abrasive tool constructed principally or practically wholly of elongated abrasive grains, arranged as above described, is particularly advantageous over similar tools, whether formed from the elongated, cubical or polyhedral type of grains, in which the grains are arranged as they happen to fall into the mold, for several reasons:—A tool constructed according to my invention is heavier, more compact, or solid, and contains a substantially greater quantity of abrasive material for the space occupied, than a similar tool in which the elongated grains are arranged as they happen to fall when poured into the mold, and closely approximates in weight and solidity to tools formed from abrasive grains which are practically equi-dimensional, or cubical, or of the polyhedral type.

The cutting effect of a tool formed of abrasive grains of a certain grit size is dependent on the number of cutting points per unit of area of the working face of the tool, and a tool formed of elongated grains arranged according to my invention presents a much greater number of cutting points per unit of area, and therefore has a much greater cutting effect, than a tool formed of similar grains, but arranged as they happen to fall into the mold. It has been the practice to increase the cutting points per unit of area over the construction last referred to by employing grains of the cubical or polyhedral types,

but of relatively smaller grit size, and while the cutting points will thus be increased, the clearance spaces between the points will be correspondingly reduced, resulting in a substantial reduction in the speed at which the tool will cut, but, where the elongated grains are employed and are arranged according to my invention, the desired increase in the number of cutting points is secured without decreasing the grit size and without materially decreasing the clearance spaces between the cutting points, so that the speed at which the tool will cut will be increased, and the tendency to generate heat when cutting will be reduced. Also, with a tool formed from the practically equi-dimensional grains, as soon as the point of a grain which engages the work is worn or broken away, the entire grain is likely to be dislodged, while with the elongated grains arranged approximately perpendicularly to the working face, the ends of the grains are gradually broken or worn off, but the sharpness remains practically the same, so that the entire grain will usually be removed in small particles and will not be dislodged, as each grain has a long, deep setting and is bound in between the grains next adjacent thereto.

Abrasives which are most commonly used are of two general types, viz.—crystalline aluminum oxide and silicon carbide. The first of these types is largely employed in grinding steel and steel alloys, as it has greater toughness than the second, which is too brittle and fragile for use on steel. Some types of aluminum oxide are too tough for use on hardened steel, as the points become dulled, so that they stop cutting and merely rub or abrade, causing heat and tending to discolor and distort the steel on which the tool is operated. To adapt such abrasives for different kinds of work, abrasive manufacturers have produced grains of different temper varying from tough to relatively fragile, the latter being used for grinding very hard steel, so that the points will shatter and constantly present new cutting points to the work. Cubical or equi-dimensional grains when employed in a grinding wheel become blunt and are torn from their settings much more quickly than the radially arranged elongated grains, for reasons already stated. Also the latter have sharper points than the former, and the angle between the sides forming the point is smaller than in the cubical grains, so that when elongated grains are employed in the construction of a wheel, and the grains are radially arranged therein, the pointed ends break off more readily than the points of the cubical grains. Consequently, the tougher types of aluminum oxide may be employed, if the grains are elongated and arranged radially, where they could not be employed if they were cubical, and the wheel thus produced is not only more efficient, but grains of the tougher types are usually approximately 50% less expensive than those of the fragile types, so that a considerable saving in manufacturing cost may be made by employing tough elongated grains, instead of fragile cubical grains for certain kinds of work. Moreover, all types of cubical and polyhedral grains are much more expensive to produce than the elongated grains, so that by employing elongated grains in the construction of abrasive tools and arranging the grains side by side in approximately perpendicular relation to the working face of the tool, I am enabled to produce a tool at a reduced cost, as compared with tools formed from abrasive grains which are practically equi-dimen-

sional, and which, in addition, compares favorably with such tools as to weight, durability and cutting points per unit of area and is substantially more efficient.

5 While the foregoing specification is largely directed to the advantages secured by an arrangement of the grains approximately perpendicularly to the abrading face of the tool, I have ascertained by experiment that as the surface speed of an 10 abrasive wheel made according to my invention is increased above an approximate point of from 5,000 to 7,000 surface feet per minute, there is an increased tendency to cause the sharp ends of grains arranged perpendicularly to the abrading 15 face to become shattered by the increased force of impact due to the increased speeds, thereby indicating that at surface speeds in excess of that above noted the thicker portions of the grains were more effective than the thinner portions, as 20 the tendency to shatter was less. This led to the conclusion, which was verified by experiment, that, at surface speeds of from 7,000 to 16,000 feet per minute, it was more advantageous to use a face in which the elongated grains were arranged parallel to, and transversely of the abrading 25 face, than to have them arranged perpendicularly thereto, as, for example, the side face of the annulus shown in Fig. 1 of the drawing, and the peripheral face of that shown in Fig. 3 of the 30 drawing. In either of these instances the grains extend transversely of the direction in which the face moves, and, while the advantage of the deep setting of the grains secured by the perpendicular arrangement is lost, the tendency to shatter at 35 high speeds is greatly reduced, and a net increase in efficiency is secured, particularly in that the advantages of increased speed of cutting due to increased surface speed are secured without too rapid deterioration of the wheel.

40 I claim:

1. An abrasive tool composed of a rigid, bonded mass of abrasive grains, a substantial portion of which are of elongated formation and are mainly positioned throughout the mass with their longer 45 dimensions extending toward the working face of the tool at a similar angle, so that one end of each of said grains may terminate in said face either initially, or subsequently from use, thereby to provide a maximum number of points effective 50 for attritive action per unit of area of said face, and to secure a maximum density of the grains per cubical unit of the tool and a maximum depth of setting of the grains.

2. An abrading tool composed of a rigid bonded 55 mass of abrasive grains, a substantial portion of which are of elongated formation and are mainly positioned side by side and end to end throughout the mass with their longer dimensions extending in approximately corresponding relation to the 60 working face of the tool.

3. An abrading tool having a circular, peripheral working face and composed of a rigid, bonded mass of abrasive grains, a substantial portion of

which are of elongated formation and are mainly arranged with their longer dimensions extending approximately radially with relation to the center of said face.

4. An annular abrading tool having flat sides 80 and a cylindrical, peripheral working face and composed of a rigid, bonded mass of abrasive grains, a substantial portion of which are of elongated formation and are mainly arranged throughout the mass in flatwise relation to said sides and in radial relation to said face. 85

5. An abrading tool composed of a rigid, bonded mass of ferrous coated, non-magnetic abrasive grains, a substantial portion of which are of elongated formation, and are mainly arranged throughout the mass with their longer dimensions extending in approximately corresponding relation to the working face of the tool. 90

6. An abrasive tool composed of a rigid, bonded mass of abrasive grains, a substantial portion of which are of elongated formation, said tool having two faces disposed approximately at right angles to each other, and said elongated grains being mainly positioned so that they extend approximately perpendicularly to one, and 100 parallel to the other of said faces. 95

7. A rotary abrasive tool composed of a rigid, bonded mass of abrasive grains, a substantial portion of which are of elongated formation, said tool having a circular peripheral face and a side 105 face, and said elongated grains being mainly positioned so that they extend approximately perpendicularly to one of said faces and transversely of the other of said faces with relation to the direction of movement thereof when the tool 110 is rotated.

8. A rotary abrasive tool composed of a rigid, bonded mass of abrasive grains, a substantial portion of which are of elongated formation, said tool having a cylindrical peripheral face, and a 115 flat side face, and said elongated grains being mainly positioned so that they extend approximately perpendicularly to one of said faces and transversely of the other of said faces with relation to the direction of movement thereof when 120 the tool is rotated.

9. A rotary abrasive tool composed of a rigid, bonded mass of abrasive grains, a substantial portion of which are of elongated formation, said tool having a cylindrical peripheral face and two flat 125 side faces, and said elongated grains being mainly positioned so that they extend approximately perpendicularly to said side faces and parallel to said cylindrical face.

10. A rotary abrasive tool composed of a rigid, 130 bonded mass of abrasive grains, a substantial portion of which are of elongated formation, said tool having a cylindrical peripheral face and parallel side faces, and said elongated grains being mainly positioned so that they extend approximately perpendicularly to said side faces and parallel to said cylindrical face. 135
